UNITED STATES PATENT OFFICE

MILES L. COLEAN, OF CHICAGO, ILLINOIS

WALL FACED WITH PANELS

Application filed March 5, 1930. Serial No. 433,225.

The present invention relates to the facing of walls with panels or thin slabs of so-called opaque structural glass or other material, and has for its object to make it possible securely to hold such panels or slabs to the face of a wall, in such a manner that the facing may be readily applied, will be securely held in place and be free to expand and contract under temperature changes.

In carrying out my invention, I provide the wall with projecting horizontal ledges spaced apart a distance slightly greater than the height of one of the panels or slabs, and with vertical webs spaced apart a distance slightly greater than the length or width of one of the panels or slabs; the ledges and webs having at their outer ends flanges projecting laterally therefrom. The panels or slabs rest at their lower edges upon the horizontal ledges and are spaced apart by the vertical webs. Holding bars, each wide enough to extend across the joint between two adjacent panels and overlie the marginal portions of both, are interlocked with the flanges on the ledges and webs; these holding bars cooperating to form outwardly from each panel a frame whose opening is somewhat smaller than the size of the panel, so that there is no possibility that any panel can free itself. However, the panels are not rigidly held in place, but may be left free to expand and contract without being restrained by the holding means. The bars may be of a material and of such contour that the net work of bars covering the finished wall constitutes or forms part of an ornamental design that adds to or completes the attractiveness of the wall.

Viewed in one of its aspects my invention may therefore be said to have for its object to produce simple and novel fastening means for holding panels or slabs to the face of a wall.

The various features of novelty whereby my invention is characterized will herein-after be pointed out with particularity in the claims; but, for a full understanding of my invention and of its objects and advantages, reference may be had to the following

detailed description taken in connection with the accompanying drawings, wherein:—

Figure 1 is an elevation of a fragment of a wall faced in accordance with my invention; Fig. 2 is a horizontal section through the wall, on a much larger scale than Fig. 1, taken on line 2—2 of Fig. 1; Fig. 3 is a section on line 3—3 of Fig. 1, the scale being the same as that of Fig. 2; Fig. 4 is a front elevation of a fragment of the wall, on the same scale as Figs. 2 and 3, before the panels and holding bars are applied to the anchors; and Fig. 5 is a perspective view of the upper end of one of the holding bars.

Referring to the drawings, 1 represents a masonry wall having horizontal mortar joints 2. Imbedded in these joints, and extending along the same from one end to the other, are thin perforated metal plates 3 that project from the face of the wall a distance somewhat greater than the thickness of the facing panels or slabs that are to be applied. The outer marginal portions of the plates are flanged upwardly, as indicated at 4. In order to provide additional stiffness when the plates are made of sheet metal, each may have two angle sections 5 and 6 welded thereto; one web or flange of the section 5 being engaged with the outer face of the wall above the plate, and the other flange extending into the wall; whereas both flanges of the section 6 may lie outside of the wall, one flange extending downwardly along the face of the wall and the other outwardly along the under side of the projecting portion of the plate. These plates are placed in position as the wall is being built; the perforations in the plate, indicated at 7, permitting the mortar to pass through and bonding the plate securely to the wall. The reinforcing sections 5 and 6, in addition to stiffening the plates, serve as gauges that permit the plates to be accurately positioned by the simple act of setting them so that the downwardly projecting flanges bear against the front face of the courses of masonry above which they respectively lie.

The panels or slabs 8 are set upon the projecting portions of the horizontal plates, 100

or what may be termed the ledges on the wall. Then, by fitting upon the flanges 4, which lie outwardly from the panels or slabs, suitable holding bars 9, each panel or slab will be held at the top and bottom against outward movement away from the wall. These holding bars may be long metal pieces of any suitable metal, each having in its rear flat face a central groove 10 extending throughout the length thereof; this groove being undercut, as indicated at 11, along the top so as to receive one of the flanges 4 when the bar is set over one of the flanges and lowered. While the holding bars along the top and the bottom of each panel might hold the same in place, I prefer to provide additional bars overlying the marginal portions at the vertical edges, so that each panel will lie behind a frame 20 whose opening is smaller than the panel. This may conveniently be accomplished by providing a series of vertical anchor plates 12 each fixed to the wall and extending between two adjacent horizontal ledges. In 25 the arrangement shown, each vertical device consists of a thin flat plate 12 bearing against the front face of the wall and welded to corresponding flanges of two light channel-shaped members 13, 13 arranged back to back, one flange 14 of each channel lying flat against the plate 12, and the other flange 15 extending parallel with the face of the wall in the same plane as the flanges 4. The vertical anchors may conveniently 30 be secured in place by means of cement nails 16 driven into the horizontal mortar joints. The vertical anchors are, of course, spaced apart at such distances that the panels may easily be slipped in place between them. In fact, the parts are so proportioned that the panels may readily be applied after all of the fixed parts of the horizontal and vertical anchors are in place. Cooperating with the vertical anchor devices are holding bars 17, similar to the bars 9, excepting that the grooves 18 are undercut at both sides, as indicated at 19, 19, in order to receive the two flanges 15 on each vertical anchor. 35 The vertical play of the horizontal holding bars is preferably great enough to permit these bars to be applied after the vertical holding bars immediately thereunder are in position. Furthermore, if desired, the lower marginal portions on the rear sides of the horizontal holding bars may be cut away, as indicated at 20, and each vertical holding bar may be provided at the top with a lip or lips 21 that will fit into 40 the slot provided between the rear face of the overlying horizontal bar and the front face of the corresponding panel along the lower portion of the horizontal bar. 45 While I have illustrated and described with particularity only a single preferred

form of my invention, I do not desire to be limited to the exact structural details thus illustrated and described; but intend to cover all forms and arrangements which come within the definitions of my invention 70 constituting the appended claims.

I claim:

1. The combination with a wall, of facing panels, of anchors fixed to the wall and comprising long thin metal strips extending 75 outward through the joints between the panels, the outer portions of the said strips having lateral flanges outwardly from said panels, and holding elements wider than the joints between the panels interlocked with 80 said flanges and covering the said joints.

2. The combination with a wall, of facing panels, long thin metal ledges fixed to the wall and extending outwardly between the meeting edges of the panels, and holding bars extending along and interlocked with 85 the outer edges of said ledges and each overlapping the adjacent marginal portions of the two panels between which the corresponding ledge lies. 90

3. The combination with a wall, of rectangular facing panels, long thin metal ledges fixed to the wall and extending outwardly between the meeting edges of the panels, the lower edge of each panel resting 95 upon one of the ledges, and holding bars interlocked with the outer portions of said ledges and cooperating with each other to form frames covering the marginal areas of all of the panels. 100

4. The combination with a masonry wall having horizontal mortar joints, of perforated horizontal metal plates extending along and embedded in the horizontal joints and projecting outwardly therefrom, vertical flanges on the outer ends of said plates, thin vertical plates extending between the horizontal plate, fastening means extending from said vertical plates into said mortar joints, the outer portions of said vertical plates being flanged laterally, facing panels resting on the projecting portions of said horizontal plates and separated from adjacent panels in the same row by the vertical plates, and holding bars interlocked with 115 the flanges on both sets of plates and each overlapping the adjacent marginal portions of the two panels positioned on opposite sides of the plate with which that bar is associated. 120

5. The combination with a masonry wall having horizontal mortar joints, of long perforated metal plates embedded in and extending along certain of said joints, said plates projecting from the wall and having their outer marginal portions bent upwardly in the form of flanges. 125

6. The combination with a masonry wall having horizontal mortar joints, of long perforated metal plates embedded in and ex- 130

- tending along certain of said joints, said plates projecting from the wall and having their outer marginal portions bent upwardly in the form of flanges, vertical plates extending along the face of the wall between the horizontal plates and having outwardly-projecting laterally-flanged portions, and means extending into said joints to hold said vertical plates to the wall.
- 10 7. The combination with a masonry wall having horizontal mortar joints, of perforated metal plates embedded in certain of said joints and projecting from the face of said wall, flanges on the outer ends of said plates and facing panels resting on said plates behind the flanges.
- 15 8. The combination with a wall, anchors fixed to the wall and extending therefrom, facing panels resting directly on the projecting portions of said anchors, flanges on said anchors extending upwardly in front of the lower marginal portions of the panels supported thereby, and detachable holders connected with said anchors and overlapping marginal portions at the top of panels directly below the anchors.

In testimony whereof, I sign this specification.

MILES L. COLEAN.
